UNITED STATES PATENT OFFICE.

JOSEPH MEGAR, OF NEW YORK, N. Y.

DESIGN FOR A BRACELET.

59,764.

Specification for Design.

Patented Nov. 22, 1921.

Application filed November 1, 1920. Serial No. 421,185. Term of patent 3½ years.

To all whom it may concern:

Be it known that I, JOSEPH MEGAR, a subject of the Government of Russia, residing at New York city, in the county of New York and State of New York, have invented a new, original, and ornamental Design for Bracelets, of which the following is a specification, reference being had to the accompanying drawing, forming part thereof, in which—

Figure 1 is a perspective view of a bracelet embracing my new design;

Fig. 2 is an end elevation thereof; and
Fig. 3 is an enlarged detailed partial sectional view.

Referring to the drawing, particularly to the features which are most prominent, the design is seen to comprise a bracelet having a countersunk channel A and beads B running circumferentially of the face thereof.

I claim:—

The ornamental design for a bracelet as shown and described.

JOSEPH MEGAR.
